UNITED STATES PATENT OFFICE.

CHARLES W. DANIELS AND JAMES MARTIN CARPENTER, OF HENRYETTA, OKLAHOMA,
ASSIGNORS OF ONE-THIRD TO MINTON M. PAYNE AND W. G. FLOURNOY, BOTH OF
HENRYETTA, OKLAHOMA.

DOUBLE-ACTING PUMP.

Application filed July 13, 1926. Serial No. 122,177.

Our invention relates to double acting pumps and more particularly to a double acting pump for oil wells.

It is a purpose of our invention to provide a pump having an outer barrel or casing and a working barrel within the same within which a piston operates which acts to pump oil both when moving in an upward and in a downward direction. In order to accomplish this purpose, suitable connections are provided between the opposite ends of the working barrel and the intake and outlet chamber of the pump, such connections being preferably mounted in the space between the outer pump barrel and the inner working barrel.

It is a further purpose of our invention to provide a new and improved mounting for a working barrel in a pump of the above mentioned character comprising a pair of partition members extending transversely of the pump barrel and defining the inlet and outlet chambers at opposite ends of the pump barrel, and to further provide a tubular perforated member for supporting the lower end of the working barrel.

It is a further purpose of our invention to provide a packing sleeve having wedging engagement with a flared extension of the working barrel, whereby said packing sleeve can be readily inserted and removed while the pump barrel is in position at the lower end of the well tubing.

Other objects and advantages of the invention will appear as the description of the accompanying drawings proceeds. However, we desire to have it distinctly understood that we do not intend to limit ourselves to the exact details shown or described, but that we intend to include as part of our invention all such obvious changes and modifications of parts as would occur to a person skilled in this art and as would fall within the scope of the claims.

In the drawings:

Fig. 1 is a vertical cross sectional view through a portion of an oil well, showing our improved pump in elevation.

Fig. 2 is a vertical longitudinal sectional view, partly broken away, of the pump.

Fig. 3 is a similar view, partly broken away, taken at right angles to Fig. 2.

Referring in detail to the drawings:

Our improved pump comprises a pump

barrel having the main body portion 10 and a tapering upper end portion 11. The main body portion 10 is provided with a reduced end portion 12 at the lower end thereof and is provided with the lugs or shoulders 13 spaced from said reduced end 12 against which the ring like partition member 14 engages. The opposite end of the member 10 is provided with internal screw threads 15 with which the screw threaded partition member 16 engages, said partition member being provided with an outwardly extending rib portion 17 mounted between the upper edge of the member 10 and the lower edge of the member 11, the member 11 being also internally threaded 18 and engaging with the threads on the member 16.

Mounted within the pump barrel 10 is the working barrel 19 which is provided with an annular rib portion 20 providing a shoulder that engages against the partition member 14. The lower end portion of the working barrel 19 is provided with an external screw thread 21 and an internal screw thread 22. Engaging with the external screw thread 21 is a locking nut 23 and engaging with the internal screw thread 22 is the reduced threaded end 24 of the tubular member 25 which is provided with perforations 26 and which has an unthreaded portion 27 fitting within the reduced end portion 12 of the member 10. A lock nut 28 engages with the screw threaded end portion 29 of the member 25 and the perforated tubular screen member 30 also screw-threadedly engages with said threaded end portion.

The upper end of the member 25 is also internally screw threaded and engages with the screw threads on the valve member 31 which is provided with a cage 32 for the ball valve 34 that is adapted to engage with the seat 35.

Operating within the working barrel 19 is a piston comprising a main body portion 36 of compressible material and the metallic end members 37 and 37' which are provided with openings for receiving the reduced portion 38 of the sucker rod 39. The lower end of the reduced portion 38 is screw threaded to receive the nut 40 for clamping the member 37 against the compressible member 36 to hold said member 36 compressed between the member 37 and the

member 37' and in snug engagement with the inner wall of the working barrel 19, the sucker rod being provided with an enlargement 41 providing a shoulder engaging against the boss 42 on the member 37' when the member 40 is tightened up. The sucker rod 39 extends upwardly through the tubing 43 as is customary and in order to provide a tight joint between the upper end of the working barrel and the sucker rod a packing sleeve 44 is provided. The packing sleeve 44 has a thickened end portion 45 that slidingly receives the sucker rod 39 and a tubular portion 46 which has a tapering wall portion gradually increasing in thickness toward the upper end 47 thereof to provide an outer tapering or flaring wall portion for the member 44. The packing member 44 engages in the upper end portion of the working barrel 19 and also engages within an outwardly flaring tubular or sleeve member 48 that screw threadedly engages with the threaded opening 49 in the partition member 16, the upper end of the working barrel 19 being also screw threadedly received within said member 16. Accordingly the packing sleeve 44 will wedge itself into position in the member 48 to provide a tight joint between the member 48 and the packing sleeve.

Within the inner enlarged bore of the packing sleeve 44 and engaging with the shoulder 50 at one end thereof is a compressible packing 51 which is held in compressed condition by engagement of the follower 52 therewith, said follower being held yieldingly in engagement with the packing member 51 by means of a compression coil spring 53 mounted between said follower and the plug 54 screw-threadedly engaging with the internal threads on the upper end 47 of the member 44. It will be seen that with the arrangement of the packing sleeve described, if it is desired to remove the piston, all that is necessary is to pull upwardly on the same and by giving a blow to the sleeve 44 the same can be dislodged from the member 48 and the sleeve and piston pulled outwardly with the sucker rod. In a similar manner the sleeve and piston can be replaced, the sleeve dropping into wedging engagement with the member 48 as the same slides down on the sucker rod 39 into position within the member 48.

The end member 11 of the pump barrel is provided with a reduced screw threaded end portion 55 with which the sleeve 56 screw-threadedly engages, said sleeve 56 also engaging with suitable threads on the end 60 of the lower section of the tubing 43 to provide a tight joint between the pump barrel and said tubing.

An inlet chamber is provided below the partition 14 within the lower end of the pump barrel, the same being indicated by the

numeral 57. Communication is established between said inlet chamber externally of the tubular member 25 and that portion lying within the tubular member 25 due to the perforations 26, the lower tubular end portion 27 of the perforated tubular member 25 acting as an intake for the pump leading from the screen member 30. The valve 34 provides for communication between the chamber within the working barrel 19 and the intake chamber 57 when the piston is on its up stroke, as the ball 34 will then be raised from its seat. A tubular conduit 58 is provided leading from the inlet chamber 57 through the partition 14 to the valve member 59 which has a seat therein for the ball valve 60, the upward movement of the ball valve 60 being limited by the cross pin 61. From said valve member 59 a tubular conduit 62 leads through the elbow 63 into the upper end of the working barrel 19, a suitable internally screw threaded opening 64 being provided for receiving the member 63. Accordingly when the piston is on its down stroke the valve 34 will engage its seat while the valve 60 will be raised from its seat and oil will be drawn into the cylinder above the piston.

The member 11 provides an outlet chamber 65 within the same that communicates with the interior of the tubing 43. A tubular conduit comprising the elbow 66 screw-threadedly engaging in a screw threaded opening 67 in the upper end of the working barrel 19 and the tubular member 68 extending through a suitable opening in the partition 16, is provided for connecting the upper end of the working barrel with the outlet chamber, a valve member 69 having a ball valve 70 engaging with a suitable seat in said valve member and limited in its movement by the cross pin 71 being provided so that said valve will be unseated when the piston is on its upward stroke but will seat when the piston is on its downward stroke. A fluid tight joint is provided between the tubular member 68 and the partition 16 by means of the compressible packing member 72 and the nut 73 screw-threadedly engaging with suitable threads on the tubular member 68. In order to provide a tight joint between the tubular member 58 and the partition 14 a compressible member 74 is inserted between the shoulder formed by the enlargement 75 on the conduit 58 and said member 14.

A tubular conduit comprising the elbow 76 and the tubular members 77 and 78 is provided for establishing communication between the outlet chamber 65 and the lower end of the working barrel 19. The elbow 76 screw-threadedly engages with a screw threaded opening 79 in the lower end of the working barrel, and the member 28 extends through an opening 80 in the partition 130

16. The tubular members 77 and 78 are connected by means of the valve member 81 which is provided with a ball valve 82 adapted to engage with a suitable seat in the valve member 81 and limited in its upward movement by means of the cross pin 83. It will be evident that when the piston is on its down stroke the valve 82 will be raised from its seat to permit the oil in the working barrel to flow through the conduit comprising the members 76, 77 and 78 into the outlet chamber 65. In order to provide a tight joint between the partition 16 and the tubular member 78 an enlargement 84 is provided 10 on the tubular member forming a shoulder between which and the partition 16 is mounted a compressible gasket 85.

It will thus be seen that the pump is double acting and that all the various connections provided to obtain the double action for the pump are mounted within the pump barrel 10 so as to obtain a compact structure which has no exposed parts that might be subject to injury. The pump barrel 10 is, of course, mounted in the hole 86 in the oil sand 87 with the screen 30 located near the bottom of the well, and the tubing 43 is mounted in the usual manner within the casing 88 which is provided with a suitable 25 shoe 89 that rests against the rock cap 90 that exists above the sand 87.

What we claim and desire to secure by Letters Patent is:

1. In a pump, a pump barrel having inlet 30 and outlet at opposite ends, a working barrel mounted in the pump barrel and having an inlet and an outlet, a piston operating in said working barrel, an inlet leading into one end of said pump barrel, a partition extending between the side walls of said working barrel and pump barrel near the inlet end thereof to provide a chamber in one end of said pump barrel with which said inlet communicates and valved inlet connections 45 leading from said chamber to opposite ends of said working barrel.

2. In a pump, a pump barrel having an inlet, a working barrel mounted in the pump barrel having spaced inlets, a piston operating in said working barrel, a partition extending between the side walls of said working barrel and pump barrel near one end thereof to provide an outlet chamber therein and valved outlet connections extending 55 from opposite ends of said working barrel through said partition into said outlet chamber.

3. In a pump, a pump barrel having an inlet, a working barrel mounted in the pump barrel having spaced inlets, a piston operating in said working barrel, a partition extending between the side walls of said working barrel and pump barrel near one end thereof to provide an outlet chamber therein 60 and valved outlet connections extending

from opposite ends of said working barrel between said barrels and through said partition into said outlet chamber.

4. In a pump, a pump barrel, a working barrel mounted therein, a piston operating 70 in said working barrel, an inlet leading into one end of said pump barrel, a partition extending between the side walls of said working barrel and pump barrel near the inlet end thereof to provide a chamber in one end 75 of said pump barrel with which said inlet communicates, valved inlet connections leading from said chamber to opposite ends of said working barrel, a partition extending between said working barrel and pump barrel near the other end thereof to provide an outlet chamber therein and valved outlet connections extending from opposite ends of said working barrel into said outlet chamber.

5. In a pump, a pump barrel, partitions 80 extending across said pump barrel near opposite ends thereof to provide an inlet chamber at one end of said barrel and an outlet chamber at the other end of said barrel, a working barrel mounted between said partitions in spaced relation to said pump barrel and having spaced intakes, an intake leading to said inlet chamber, a conduit leading from said outlet chamber, a piston operating in said working barrel and valved conduits leading from opposite ends of said working barrel to said outlet chamber.

6. In a pump, a pump barrel, partitions 85 extending across said pump barrel near opposite ends thereof to provide an inlet chamber at one end of said barrel and an outlet chamber at the other end of said barrel, a working barrel mounted between said partitions in spaced relation to said pump barrel, an intake leading to said inlet chamber, 90 a perforated tubular member extending from said intake to said working barrel, a conduit leading from said outlet chamber, a piston operating in said working barrel and valved conduits leading from opposite ends of said working barrel to said outlet chamber.

7. In a pump, a pump barrel, partitions 95 extending across said pump barrel near opposite ends thereof to provide an inlet chamber at one end of said barrel and an outlet 100 chamber at the other end of said barrel, a working barrel mounted between said partitions in spaced relation to said pump barrel, an intake leading to said inlet chamber, a perforated tubular member extending from said intake to said working barrel, a valved inlet leading from said inlet chamber into said working barrel, a conduit leading from said outlet chamber, a piston operating in 105 said working barrel and valved conduits leading from opposite ends of said working barrel to said outlet chamber.

8. In a pump, a pump barrel, partitions 110 extending across said pump barrel near opposite ends thereof to provide an inlet cham- 115

ber at one end of said barrel and an outlet chamber at the other end of said barrel, a working barrel mounted between said partitions in spaced relation to said pump barrel and having spaced intakes, an intake leading to said inlet chamber, a conduit leading from said outlet chamber, a piston operating in said working barrel, one end of said working barrel being flared, a tapered pack-

ing sleeve wedgingly engaging with said flared end thereof, and valved conduits leading from opposite ends of said working barrel to said outlet chamber.

In testimony whereof we affix our signatures.

CHARLES W. DANIELS.
JAMES MARTIN CARPENTER.
